UNITED STATES PATENT OFFICE.

IRVING KAUFMAN, OF BALTIMORE, MARYLAND.

PIN-TICKET.

1,030,471.

Specification of Letters Patent. Patented June 25, 1912.

Application filed January 22, 1912. Serial No. 672,650.

To all whom it may concern:

Be it known that I, IRVING KAUFMAN, a citizen of the United States, residing at Baltimore city, State of Maryland, have invented certain new and useful Improvements in Pin-Tickets, of which the following is a specification.

My invention relates to improvements in pin tickets or tags, and particularly to that 10 class of such devices which are adapted to be used for marking goods to indicate the cost and sale price and other memoranda, and has for its object the production of a novel and efficient pin ticket or tag adapted 15 to be fastened to fabrics of various kinds, such as clothing or other objects as may be desired.

The further object of the invention is to provide a ticket or tag of this character 20 whereby the pin or fasteners are covered or protected in such a manner that they will not enter or catch upon adjacent articles or materials, nor injure the hands of those who are called upon to handle the ticketed objects.

With the foregoing objects in view, my invention consists in certain novel features of construction, and combinations of parts which will be hereinafter described and 30 pointed out in the claim.

In the accompanying drawings forming a part of this specification in which is illustrated a preferred embodiment of my invention, Figure 1 is a perspective view of 35 the ticket; Fig. 2 is a back view of the same as applied to a piece of fabric; Fig. 3 is a front view similar to Fig. 2; Fig. 4 is a section on line 4—4 of Fig. 2, and Fig. 5 is an edge view with the ticket bent to permit the 40 pins to be inserted under the flaps.

A, indicates the tag or ticket, which may be of any suitable length or width, and made from any suitable material, such as card board and the like, capable of being readily 45 handled and easily marked. The ticket is preferably of an oblong shape, and folded at a point substantially midway its length as indicated at 1 to form the members 2 and 3. Provided in the upper end portion of the 50 member 3 are flaps 4, cut from the body part of the member and are integral therewith, the cut portions terminating in apertures 5 to prevent the cut portion from further tearing in the operation of the device, and to 55 permit the legs of the pin 6 to pass more freely under the flaps in the manner to be

hereinafter described. These flaps are not necessarily limited to the particular design, shape or location as shown in the drawing, but may be other than that as shown to 60 meet the particular requirements to which the ticket is subjected. Provided in the opposite member 2, at the upper end portion thereof is secured the fastening device consisting of a staple or pin 6, provided with 65 pointed legs 7, the fastener being of a well known staple form, and made from flexible wire, as is usual. The legs being pointed as to render them to easily penetrate the fabric to which the ticket is attached, the pin being 70 preferably permanently secured to the ticket. Provided in the upper end portion of the member 3, located between the flaps 4, and oppositely disposed to the legs 7 of the pin 6 on the member 2, is a transverse 75 aperture or slot 8, through which the legs 7 are extended in the manner of securing the ticket on the fabric, now about to be described.

My invention is operated as follows: The 80 fabric 9 or other article to which the ticket is to be attached, is inserted between the members 2 and 3 of the ticket A, the pointed legs 7 of the pin 6 made to penetrate the fabric 9, and extend through the slot 8 of 85 the member 2, the ticket is then bent to assume the position shown in Fig. 5, which causes the flaps 4 to open as shown in this figure, the legs 7 are then bent outwardly and downwardly upon the fabric as shown 90 in Figs. 2 and 4, the ticket upon being released from the bent position shown in Fig. 5 will then assume its normal position, and when in its normal position after having been secured on the fabric, the pointed legs 95 7 will be housed beneath the flaps 4, as shown in Figs. 2 and 4, whereby they are prevented from catching upon adjacent articles or materials, or injuring the hands of those called upon to handle the objects to 100 which the tickets are attached.

Slight changes and alterations might be resorted to in the form and arrangement of the several parts described without departing from the spirit and scope of my invention as defined by the appended claim, and hence I do not wish to limit myself to the exact construction as herein set forth; but,

Having fully described my invention, what I claim, and desire to secure by Letters Patent, is;

A ticket of the character described com-

prising two members having an aperture and a fastening device respectively, said fastening device having a pair of terminals which are adapted to pass through the aperture, 5 and means for housing the terminals, said means consisting of suitable slits cut in one member to form oppositely disposed flaps, adapted to open upon the ticket being pressed in convexed position and receive 10 said terminals, and close when the pressure

upon the ticket is released thereby forming a housing for the said terminals, substantially as described.

In testimony whereof I affix my signature in presence of two witnesses.

IRVING KAUFMAN.
